227,713

TOBACCO PIPE OR SIMILAR ARTICLE

William Geiser, 903 Alta St., Monrovia, Calif. 91016

Filed Apr. 26, 1971, Ser. No. 137,745

Term of patent 14 years

Int. Cl. D27—02

U.S. Cl. D85—8 A

FIG. 1.

FIG. 3.

FIG. 2.

FIG. 4.

FIG. 1 is a perspective view of a tobacco pipe or similar article, showing my new design;

FIG. 2 is a top plan view;

FIG. 3 is a rear elevational view; and

FIG. 4 is a side elevational view, the opposite side being substantially a mirror image thereof.

I claim:

The ornamental design for a tobacco pipe or similar article, as shown and described.
